CUP

Christy M. Del Mas, New York, N. Y.

Application March 28, 1952, Serial No. 19,099

Term of patent 14 years

(Cl. D44—9)

To all whom it may concern:

Be it known that I, Christy M. Del Mas, a citizen of the United States of America, residing at city, county, and State of New York, have invented a new, original, and ornamental Design for a Cup, of which the following is a specification, reference being had to the accompanying drawing, forming part thereof.

The figure is a perspective view of a cup embodying my new design. The side opposite is similar to the side shown and the bottom of the cup is plain.

I claim:

The ornamental design for a cup, as shown and described.

CHRISTY M. DEL MAS.
